ATTORNEY

UNITED STATES PATENT OFFICE.

JOSHUA S. GRAHAM, OF DETROIT, MICHIGAN.

HATPIN-GUARD.

1,328,954.

Specification of Letters Patent. Patented Jan. 27, 1920.

Application filed October 17, 1917. Serial No. 197,114.

To all whom it may concern:

Be it known that I, JOSHUA S. GRAHAM, a citizen of the United States, residing at Detroit, in the county of Wayne and State 5 of Michigan, have invented certain new and useful Improvements in Hatpin-Guards, of which the following is a specification.

My invention relates to new and useful improvements in hat pin guards and is 10 particularly of the type which are passed over the pointed end of the hat pin to prevent the loss of the pin or the injury ordinarily inflicted upon persons coming into contact with the unprotected point of the 15 hat pin.

An important object of my invention is to provide a device of the above mentioned character including a spring pressed member which is urged against the pin inserted 20 in the device, thereby making a frictional contact with the pin and preventing the device from being lost from the hat pin, or the pin from becoming lost.

Another object of my invention is to provide a device of the above mentioned character which is strong, durable, inexpensive to manufacture and efficient in practice.

Other objects and advantages will be apparent during the course of the following 30 description.

In the accompanying drawings forming a part of the description and wherein like numerals are employed to designate like parts throughout the same,

35 Figure 1 is a side elevation of the device attached to a hat pin.

Fig. 2 is a vertical sectional view of the same, and

40 Fig. 3 is a sectional view taken on the line 3—3 of Fig. 1.

In the accompanying drawings wherein is shown a preferred embodiment of my invention the numeral 4 designates an ordinary hat pin provided upon the end opposite its 45 point, with a head 5 of any suitable design.

My invention consists of a head 6 of any desired design, which is provided with a recess to receive member 7, having a slightly reduced portion 8 to form a finger grip 50 whereby the device may be readily pushed over the point of the pin. This member 7 is provided with a bore therethrough to receive the pointed end of the pin. This bore is enlarged to form the cavity or chamber 9. Communicating with this cavity at its 55 end adjacent the bore, are two oppositely

arranged openings, which pass through the walls of the cavity.

The loss preventing or locking structure of the device, consists of a locking member 10, 60 having a substantially wedge shaped opening 11 therethrough, and is arranged to operate in the cavity 7 adjacent the bore therein. The opening 11 is arranged so that the wedge shaped sides of this opening engage 65 with the hat pin when the pin is inserted into the chamber 9. It will be noted that the opening 11 extends the full width of the locking member 10 and is of the same dimensions throughout its entire length. By this 70 construction it will be apparent that both sides of the wedge shaped opening will engage with the hat pin when inserted into the device, and will exert a wedging action upon the pin thereby holding it in the cavity 9 75 more firmly than has been experienced in former devices. The top of this opening is substantially circular and terminates at its lower end in the said wedge shape. Two oppositely arranged threaded openings are pro- 80 vided in the locking member and are adapted to be aligned with the oppositely arranged openings in the walls of the cavity 9, to receive a lower guide pin 12, and a push pin 13 which is provided with a head upon its 85 outer end. The threaded portion of these pins is adapted to be received in the threaded openings in the locking member, while the other portions are adapted to pass through and beyond the openings in the cavity 90 walls, and thereby form a guide in order that the locking member may reciprocate therein. A spring 14 having one end secured to the inner wall of the cavity 9, and the opposite end thereof bifurcated to receive the pin 12, is adapted to normally urge the opening in the locking member out of alignment with the bore to receive the pin. It will be noted that the free end of the 95 spring engages the locking member so that 100 the sides of the wedge shaped portion of the opening 11 are normally urged into a wedging action with the pin when the pin is inserted in the cavity 9. At the outer end 105 of the bore the walls thereof are flared outwardly to readily guide the point of the pin into the guard.

To use the guard, the ordinary hat pin 4 is passed through the hat and hair of the wearer in the usual manner until the point 110 thereof extends beyond one of the sides of the hat. The guard is grasped so that one

2

finger exerts a pressure on the head of the pin 13 and slides the locking member down against the tension of the spring 14. In this position the substantially circular portion 5 of the opening 11 is in alinement with the bore through the guard. The pointed end of the pin is then guided into the bore and through the opening in the locking member 10 until the point of the pin engages the 10 bottom of the recess formed in the head 6. When the pin attains this position, the pressure upon the pin 13 is released and the spring 14 forces the sides of the wedge shaped portion of the opening in the locking 15 member against the pin and thereby prevents the guard from becoming disengaged with the pin. To release the pin from the guard, the push pin is actuated to aline the opening 11 with the bore through the member 7 and the pin is then withdrawn. 20

It is to be understood that the form of my invention herewith shown and described is to be taken as a preferred embodiment of the same and that various changes in the 25 shape, size and arrangement of parts may be resorted to without departing from the spirit of the invention or the scope of the subjoined claim.

Having described my invention I claim:

A hat pin guard comprising an elongated 30 hollow member thus forming an internal chamber, said member also being provided with a reduced longitudinally extending bore communicating with one end of said chamber, a plate like locking member having pins extending from opposite ends thereof and passing outwardly through said member to constitute a guide for said locking member, whereby the locking member may be shifted, said plate like locking member also having an opening therein which is wedge shaped at one end, one of said pins having a head on its outer end, a flat spring fixed within said first mentioned member and extending longitudinally of said chamber, said flat spring having a bifurcated end engaging about one of said pins to force the locking member in one direction to cause the opening thereof to slightly extend across the inner end of said bore, as and for the 40 45 50 purposes set forth.

In testimony whereof I affix my signature in presence of two witnesses.

JOSHUA S. GRAHAM.
